Primary Examiner — Marissa J. Cash(74) *Attorney, Agent, or Firm* — Foley & Lardner LLP(57) **CLAIM**

The ornamental design for a launcher as shown and described.

DESCRIPTION

FIG. 1 is a bottom, front, right perspective view of the launcher;

FIG. 2 is a front elevation view thereof;

FIG. 3 is a rear elevation view thereof;

FIG. 4 is a left side view thereof;

FIG. 5 is right side view thereof;

FIG. 6 is a top plan view thereof; and,

FIG. 7 is a bottom plan view thereof.

The ornamental design which is claimed is shown in solid lines in the Figures. The broken lines in the drawings illustrate portions of the launcher that form no part of the claimed design.

1 Claim, 4 Drawing Sheets(56)
